HIS ATTORNEY

UNITED STATES PATENT OFFICE

NICOLA STRAMAGLIA, OF CHICAGO, ILLINOIS

DRYING BASKET

Application filed October 2, 1929. Serial No. 396,856.

This invention relates to certain novel improvements in drying baskets and more particularly to a drying basket intended for use in a laundry and the like and has for its principal object the provision of an improved construction of this character which will be highly efficient in use and economical in manufacture.

The salient object of my invention is to provide a basket which will be arranged in the manner which will permit the expeditious dumping of the clothes therefrom when desired.

Another object of the invention is to provide a basket of the above described character which will be so arranged that it may be expeditiously mounted on a truck in a manner which will prevent ready displacement therefrom in order that transportation thereof will be facilitated.

Another object of the invention is to provide an improved retaining arrangement for the mechanism which will comprise a member that may be expeditiously removed when so desired.

A further object of the invention is to provide an arrangement which will retain the removable member until releasing thereof is desired.

Other objects will appear hereinafter.

The invention consists in the novel combination and arrangement of parts to be hereinafter described and claimed.

The invention will be best understood by reference to the accompanying drawing, showing the preferred form of construction and in which:

Fig. 1 is a perspective view depicting a preferred form of construction for my invention in association with a washing machine from which machine the clothes are intended to be removed and introduced into my improved device;

Fig. 2 is a fragmentary elevational view depicting the truck or transporting device employed in connection with my invention;

Fig. 3 is a view partly in elevation and partly in section depicting my improved basket;

Fig. 4 is a top plan view of the device illustrated in Fig. 3;

Fig. 5 is a view taken substantially on the line 5—5 on Fig. 3; and

Fig. 6 is a sectional view taken substantially on the line 6—6 on Fig. 5.

In the accompanying drawing wherein I have illustrated the preferred form of construction for my invention 10 generally indicates a washing machine of the laundry type which is divided into a plurality of washing compartments 11 into which the clothes are introduced and in which the clothes are agitated in the presence of the cleansing medium. After the washing has been carried out for a predetermined length of time the saturated clothes are removed from the washing machine and are transported to a drying machine and my improved device is intended to be used in connection with this transportation.

My improved device includes a substantially cylindrical basket member 12 which is preferably formed from a suitable perforated material such as wire mesh screen and which is open at the upper and lower ends thereof. The upper end of the basket 12 is directed inwardly to provide a reduced opening.

A supporting bracket 13 is provided which comprises right angularly extending arms that may be disposed to extend diametrically across the upper end of the basket 12. Chains 14 are secured to the arms of the bracket 13 adjacent the ends thereof. These chains are detachably connected to the upper end of the basket 12 in order that the basket may be lifted in a manner to be set forth. These chains 14, when so connected, extend across the basket 12 as chords thereof, as best illustrated in Fig. 4.

As best illustrated in Fig. 5 a chain 16 is provided at the lower end of the basket 12. This chain 16 is secured to the basket 12 at spaced apart points and are of greater length than chordal lines drawn between the attaching points. On the chain 16 intermediate the attached portions thereof rings 17 are provided. A retaining member in the

80

75

85

90

95

100

form of a cord 18 is provided which is passed through the rings 17.

Arranged at the center of the basket 12 is a conical member 19 which, as best illustrated in Fig. 6, is preferably of less height than the basket 12. The upper end of this conical member 19 is truncated and an attaching loop 20 is mounted at this end. Depending from the point of intersection of the arms of the bracket 13 is a hook element 21 and the attaching loop 20 is disposed in this hook element 21 to retain the conical member 19 in the basket 12. It is manifest that the lower end of the conical member 19 is, therefore, disposed above the lower end of the basket 12.

The attaching cord 18 is arranged to extend around the member 19 adjacent the base thereof and, therefore, the rings 17 may be drawn into engagement with the conical member 19, and, therefore, the intermediate portions of the chain 16 will be arranged to extend inwardly and upwardly as is best illustrated in Figs. 5 and 6 and by referring to Fig. 5 it may be seen that by so arranging the chains a substantially star shaped figure will result. This arrangement of the chains provides with the member 19 a bottom for the basket 12.

In order to facilitate transportation of the device I provide a vehicle in the form of a truck 22 which is preferably mounted on wheels or castors 23 to facilitate transportation thereof. On the truck 22 I fixedly mount a conical member 24 which is of a size that will permit this conical member 24 to be arranged interiorly of the conical member 19.

In use, the conical member 19 is arranged interiorly of the basket 12 and the attaching cord 18 is passed about the lower end thereof to arrange the chain 16 in the manner set forth and the attaching cord 18 has the end portions thereof knotted or otherwise retained as shown at 25. The basket 12 is then arranged on the truck 22 with the conical member 24 arranged interiorly of the conical member 19. The clothes are then removed from one of the washer compartments 11 and are introduced into the basket 12. The bracket 13 is then disposed over the upper end of the basket 12 and the chains 14 are attached to the upper end of the basket 12. The hook element 21 is passed through the retaining loop 20. The device is then ready for transportation to a drying mechanism as for example a centrifugal drier. The basket 12 is then removed from the truck 22 and introduced into this centrifugal drier and the cleansing medium is extracted from the saturated clothes through the basket 12. The device is then removed from the drier and is transported on the truck 22 and cone 24 to a so called sorting table. The hook 21 is then detached from the loop member 20. A suitable hoisting mechanism is attached to the

loop 15, and, therefore, the basket 12 may be raised independently of the core 19. It is manifest that the clothes which have been introduced into the basket 12 will be resting on the chain 16. By reason of the weight of these clothes and the frictional adherence between the cones 19 and 24, the hook 21 having been detached from the loop member 20, the cone 19 will remain on the cone 24 as the basket 12 is raised. Therefore, the chain 16 will retain the star like formation but instead of extending upwardly with respect to the lower end of the basket 12 this chain will extend downwardly and will retain the clothes in the basket 12. The hoisting device then transports the basket 12 to a position above the sorting table and by reason of the fact that the chain 16 is depending it is manifest that access to the knot 25 may be readily attained. By untying this knot 25 it is manifest that the chain 16 will be released and, therefore, the clothes will fall from the basket 12 onto the sorting table. The device will then be arranged in the manner heretofore set forth and the above described operation will be repeated.

It is manifest from the foregoing description that I have provided an arrangement which will greatly facilitate the transportation of clothes and other material in a laundry or the like. It is also apparent that the device is arranged in a manner which will permit the expeditious removal of the clothes from the member into which they are introduced for transportation.

While I have illustrated and described the preferred form of construction for carrying my invention into effect, this is capable of variation and modification, without departing from the spirit of the invention. I, therefore, do not wish to be limited to the precise details of construction set forth, but desire to avail myself of such variations and modifications as come within the scope of the appended claims.

Having thus described my invention what I claim as new and desire to protect by Letters Patent is:

1. In laundry apparatus, a gasket having an open bottom, flexible means attached to said basket adjacent said bottom, a member adapted to be disposed within said basket and to be releasably engaged therein by said flexible means and when therein co-operating with said flexible means to provide a bottom for, and to retain articles in, said basket, and means providing releasable engagement between said flexible means and said member and which may be released from engagement with said member by raising the basket independently of said member, thus permitting the articles to fall from the basket through said bottom thereof thus opened.

2. In laundry apparatus, a basket having an open bottom, flexible means attached to

5 said basket adjacent said bottom, a member adapted to be disposed within said basket and to be releasably engaged therein by said flexible means and when therein co-operating with said flexible means to provide a bottom for, and to retain articles in, said basket, 70
 10 with said member by raising the basket independently of said member, thus permitting the articles to fall from the basket through said bottom thereof thus opened, and means to which said member and basket may be attached so that both may be hoisted together or the basket independently of said member.

3. In laundry apparatus, a basket having an open bottom, flexible means attached to said basket adjacent said bottom, a member 20 adapted to be disposed within said basket and to be releasably engaged therein by said flexible means and when therein co-operating with said flexible means to provide a bottom for, and to retain articles in, said basket, 25 means providing releasable engagement between said flexible means and said member and which may be released from engagement with said member by raising the basket independently of said member, thus permitting the articles to fall from the basket through said bottom thereof thus opened, means adapted to have detachable connection with said basket at the top thereof and enabling the basket to be hoisted, and an element attached to said last-mentioned means and adapted to be connected to said member so that said member and basket may be hoisted together or the basket independently of said member.

40 4. In laundry apparatus, a basket having an open bottom, flexible means attached to said basket adjacent said bottom, a hollow conical member having an open base and adapted to be disposed within said basket and to be releasably engaged therein by said flexible means and when therein co-operating with said flexible means to provide a bottom for, and to retain articles in, said basket, 45 means providing releasable engagement between said flexible means and said conical member and which may be released from engagement with said conical member by raising the basket independently of said conical member, thereby permitting said articles to fall from the basket through said bottom thereof thus opened, a vehicle, and a conical element on said vehicle onto which said hollow conical member may be telescoped so that said basket, articles, and conical member may be transported on said vehicle, means adapted to have detachable connection with said basket at the top thereof, and an element attached to said last-mentioned means attachable to said hollow conical member so that said basket and hollow conical member may be hoisted together onto and off said conical element and vehicle or said basket be raised therefrom independently of said hollow conical member so that said articles may be discharged from the basket.

50 5. In laundry apparatus, a basket having an open bottom, flexible means attached to said basket adjacent said bottom, a hollow conical member having an open base and adapted to be disposed within said basket and to be releasably engaged therein by said flexible means and when therein co-operating with said flexible means to provide a bottom for, and to retain articles in, said basket, 55 means providing releasable engagement between said flexible means and said conical member and which may be released from engagement with said conical member by raising the basket independently of said conical member, thereby permitting said articles to fall from the basket through said bottom thereof thus opened, a vehicle, and a conical element on said vehicle onto which said conical member may be telescoped so that said basket, articles, and conical member may be transported on said vehicle.

60 5. In laundry apparatus, a basket having an open bottom, flexible means attached to said basket adjacent said bottom, a hollow conical member having an open base and adapted to be disposed within said basket and to be releasably engaged therein by said flexible means and when therein co-operating with said flexible means to provide a bottom for, and to retain articles in, said basket, 65 means providing releasable engagement between said flexible means and said conical member and which may be released from engagement with said conical member by raising the basket independently of said conical member, thereby permitting said articles to fall from the basket through said bottom thereof thus opened, a vehicle, and a conical element on said vehicle onto which said conical member may be telescoped so that said basket, articles, and conical member may be transported on said vehicle.

65 to be releasably engaged therein by said flexible means and when therein co-operating with said flexible means to provide a bottom for, and to retain articles in, said basket, 70 means providing releasable engagement between said flexible means and said conical member and which may be released from engagement with said conical member by raising the basket independently of said conical member, thereby permitting said articles to fall from the basket through said bottom thereof thus opened, a vehicle, and a conical element on said vehicle onto which said conical member may be telescoped so that said basket, 75 articles, and conical member may be transported on said vehicle, and means arranged over the upper end of said basket to which said basket and said hollow conical member may be attached so that both may be moved together onto and off said conical element and vehicle and said basket be raised therefrom independently of said conical member.

80 6. In laundry apparatus, a basket having an open bottom, flexible means attached to said basket adjacent said bottom, a hollow 90 conical member having an open base and adapted to be disposed within said basket and to be releasably engaged therein by said flexible means and when therein co-operating with said flexible means to provide a bottom 95 for, and to retain articles in, said basket, means providing releasable engagement between said flexible means and said conical member and which may be released from engagement with said conical member by raising the basket independently of said conical member, thereby permitting said articles to fall from the basket through said bottom thereof thus opened, a vehicle, and a conical element on said vehicle onto which said hollow conical member may be telescoped so that said basket, articles, and conical member may be transported on said vehicle, means adapted to have detachable connection with said basket at the top thereof, and an element attached to said last-mentioned means attachable to said hollow conical member so that said basket and hollow conical member may be hoisted together onto and off said conical element and vehicle or said basket be raised therefrom independently of said hollow conical member so that said articles may be discharged from the basket.

100 7. In laundry apparatus, a basket having an open bottom, flexible means attached to said basket about the bottom thereof, a member adapted to be disposed within said basket, and when therein to be releasably engaged by said flexible means and providing with said flexible means an article retaining bottom for said basket, means adapted to have detachable connection with said basket at the top thereof, means providing releasable engagement between said flexible means and member adjacent the bottom of the lat-

- ter, and an element attached to said second-named means and adapted to be detachably connected to said member so that said basket and member may be hoisted together or said basket hoisted independently of said member to permit said third-named means to be disengaged from said member and articles in said basket to be discharged therefrom through said bottom thus opened.
8. In laundry apparatus, a basket having an open bottom, flexible means attached to said basket about the bottom thereof, a hollow member having an open base and adapted to be disposed within said basket and when therein to be releasably engaged by said flexible means, and when in said basket providing with said flexible means an article retaining bottom for said basket, means adapted to have detachable connection with said basket at the top thereof, means providing releasable engagement between said flexible means and member adjacent the bottom of the latter, an element attached to said second-named means and adapted to be detachably connected to said member so that said basket and member may be hoisted together or said basket hoisted independently of said member to permit said third-named means to be detached from said member and articles in said basket to be discharged therefrom through said bottom thus opened, a member over which said hollow member is adapted to be telescoped through said open base, and a vehicle supporting said last-mentioned member for transportation of said basket and hollow member therewith.
9. In laundry apparatus, a vehicle and a conical member thereon, a basket having an open end, a hollow conical element having an open base, said hollow conical element being adapted to be disposed within said basket and being adapted to be telescoped onto said conical member through said open base, flexible means attached to said basket adjacent said open end thereof, means providing releasable engagement between said flexible means and said hollow conical element adjacent said open base of the latter and which may be released from engagement with said hollow conical element by raising said basket independently of said hollow conical element, said hollow conical element cooperating with said flexible means to provide an article-retaining bottom for said basket at said open end thereof, a member arranged over the top of said basket, means for attaching said last-named member to the basket, and means for attaching said last-named member to said hollow conical element.
10. In laundry apparatus, a basket having an open bottom, flexible means attached to said basket about said bottom, a member in said basket releasably engageable by said flexible means to provide therewith an

article-retaining bottom for said basket, a member arranged over the top of said basket, means for attaching said last-named member to the basket, and means for attaching said last-named member to the first-named member.

11. In laundry apparatus, a basket having an open bottom, flexible means attached to said basket about said bottom, a hollow member in said basket having an open base and releasably engageable by said flexible means to provide therewith an article-retaining bottom for said basket, means arranged over the top of said basket including elements detachably attachable to said basket and including an element detachably attachable to said member, a vehicle, and a member on said vehicle receivable into said hollow member through said open base.

In testimony whereof I affix my signature.

NICOLA STRAMAGLIA.
